UNITED STATES PATENT OFFICE.

HIRAM A. SMITH, OF KALAMAZOO, MICHIGAN.

MOLD.

1,325,050.

Specification of Letters Patent. Patented Dec. 16, 1919.

Application filed April 10, 1919. Serial No. 288,901.

To all whom it may concern:

Be it known that I, HIRAM A. SMITH, a citizen of the United States, residing at Kalamazoo, county of Kalamazoo, State of Michigan, have invented certain new and useful Improvements in Molds, of which the following is a specification.

This invention relates to improvements in molds.

10 The main objects of this invention are:

First, to provide an improved mold for the manufacture of staves or blocks for circular structures such as silos, bins, tanks and the like.

15 Second, to provide an improved mold for the manufacture of staves and blocks for circular structures of different diameter.

Third, to provide an improved mold having the above advantages which is simple in 20 its structure and use or manipulation.

Further objects, and objects relating to structural details will definitely appear from the detailed description to follow.

Figure I is a plan view of a mold embodying the features of my invention.

Fig. II is a cross section on a line corresponding to line 2—2 of Fig. I with the mold being shown filled.

Fig. III is an enlarged detail section 30 through one of the side members on a line corresponding to line 3—3 of Fig. I.

Fig. IV is a detail section on a line corresponding to line 4—4 of Figs. II and V, showing the means for positioning the side 35 members and details of the connections for the side and end members.

Fig. V is a detail section on a line corresponding to the broken line 5—5 of Figs. II and III.

40 Fig. VI is a detail view of an end member having its dowel openings positioned so as to support the side members with their faces at a different angle relative to the plane of the pallet.

Fig. VII is a detail view of a wall formed 45 of staves of the type my improved mold is designed to produce.

In the drawing, similar reference characters refer to similar parts throughout the 50 several views, and the sectional views are taken looking in the direction of the little arrows at the ends of the section lines.

Referring to the drawing, the pallet 1 is of the proper dimensions to receive the mold 55 side and end members which are arranged thereon, as shown in Fig. I. The faces of

the side members 2 and 3 are conformed to provide the molded blocks or staves 4 with tongues 5 and grooves 6, the side member 2 having a longitudinal groove 7 therein, 60 while the side member 3 has a longitudinal rib 8. The side members have flange-like ribs 9 at their edges forming rabbet-like grooves at the edges of the blocks, which when the blocks or staves are laid in a wall, 65 as shown in Fig. VII, may be filled with cement. The dowel members are provided with outwardly projecting arms 10 at their ends having dowel pins 11 thereon.

I provide a plurality of sets of coacting 70 end members 12, which are adapted to be interchangeably associated with the side members and have dowel openings 13 adapted to be engaged with the pins 11 of the arms 10 of the side members, thereby 75 supporting the side members at an angle to the face of the pallet and determining the angle of the ends of the blocks or staves formed by the mold. The dowel openings of the end member sets are differently positioned 80 as shown in the end member 12', Fig. VI, so that when the different sets of end members are associated with the side members they are supported at different angles, there being a set of end members provided 85 for each diameter of wall which it is desired to manufacture. The end members are preferably provided with suitable indicia indicating the diameter so that unskilled workmen will have no difficulty in manufacturing the various blocks or staves which 90 may be desired.

In practice, the side and end walls are detachably secured together and preferably by means of bolts 14 and the clamps 15, the 95 bolts 14 being disposed through diagonally opposite arms and diagonally opposite ends of the associated end members so that one side and end member is handled as a unit in positioning on the pallet and removing 100 therefrom. The clamps 15 are mounted upon diagonally opposite arms to be swung over the ends of the end members, as clearly shown in Fig. I, thus providing a means for quickly securing the parts.

A number of pallets may be provided so that blocks may be allowed to rest thereon until sufficient is set for handling or may be completely cured while resting on the pallets, it being practical to remove the side 110 and end walls of the mold within a short time after the block is formed. The length

of time depends more or less on the character of the material used, that is, the amount of water which it contains.

Having thus described my invention, what I claim as new and desire to secure by Letters Patent is:

1. In a mold, the combination of a pallet, side members resting on said pallet and having outwardly projecting arms at their ends provided with dowel pins, the faces of the arms being flush with the ends of the side members, a plurality of sets of end members adapted to be interchangeably associated with said side members and having dowel openings thereon, coacting with the dowel pins of said side member arms, the dowel openings of the different sets of members being differently positioned so that when the dowels of a set are engaged the faces of the side members are supported at a predetermined angle relative to the plane of the pallet, bolts for detachably securing one side member to one end member associated therewith, so that such side and end member may be handled as a unit disposed through diagonally opposite arms of the side members and diagonally opposite ends of the end members, and clamps for detachably securing the other side member arms to the other ends of the end members.

2. In a mold, the combination of a pallet, side members resting on said pallet and having outwardly projecting arms at their ends provided with dowel pins, a plurality of sets of end members adapted to be interchange-

ably associated with said side members and having dowel openings thereon coacting with the dowel pins of said side member arms, the dowel openings of the different sets of members being differently positioned so that when the dowels of a set are engaged the faces of the side members are supported at a predetermined angle relative to the plane of the pallet, and means for detachably securing the coacting side and end members with their dowels in engagement.

3. In a mold, the combination of a pallet having an unobstructed flat face, removable side members resting on said pallet, a plurality of sets of removable end members adapted to be interchangeably associated with said side members, the said side and end members having co-engaging positioning means for the side members, the positioning means of the different sets of members being varied so that by interchanging the sets of end members, the faces of the side members are supported at different predetermined angles relative to the plane of the pallet, and means for detachably securing said side and end members with said positioning means in engagement.

In witness whereof I have hereunto set my hand and seal in the presence of two witnesses.

HIRAM A. SMITH. [L.S.]
